ASSIGNORS TO ELECTRIC BOAT COMPANY, OF NEW YORK, N. Y., A CORPORATION
OF NEW JERSEY.

INTERNAL-COMBUSTION ENGINE.

1,180,636.

Specification of Letters Patent. Patented Apr. 25, 1916.

Application filed February 9, 1915. Serial No. 6,986.

To all whom it may concern:

Be it known that we, GREGORY C. DAVISON and JOHN W. ANDERSON, citizens of the United States, residing at New London, in the county of New London and State of Connecticut, have invented certain new and useful Improvements in Internal-Combustion Engines; and we do hereby declare the following to be a full, clear, and exact description of the invention, such as will enable others skilled in the art to which it appertains to make and use the same.

This invention relates to internal combustion engines and more particularly to mechanism for effecting reversal of the direction of operation of such an engine and for starting the engine in operation in either direction.

The invention involves the provision of a simple form of reversing gearing by which certain of the operating mechanism of the engine may be shifted to adapt the engine for rotation in the opposite direction, this gearing being such that the changed relation of the operating mechanism may be established before the engine is started in rotation in the reverse direction.

Another feature of the invention involves the provision of pneumatically operated devices for effecting the change in the relation of the operating mechanism incident to changing the direction of rotation of the engine.

The invention also involves the provision of certain locking devices whereby, when the parts of the operating mechanism are set in the positions for rotation of the engine in the desired direction, they will be locked in that position and positively held against accidental displacement. These locking devices are so constructed that they are automatically unlocked without requiring additional manipulation on the part of the operator when effecting the necessary change in the relation of the operating mechanism incident to reversing the direction of rotation of the engine.

The invention also involves the provision of an improved form of starting mechanism employing compressed air as the starting medium, which air is admitted to the cylinders of the engine and acts on the pistons therein. This starting mechanism is combined with the mechanism for reversing the

engine so that the manipulation of a single valve in the conduit leading from the compressed air supply results in establishing the relation of the operating mechanism incident to rotation in the desired direction and then, without further manipulation, admits air or effects the admission of air to the cylinders for starting the engine.

These and other features of the invention will be better understood by reference to the following description taken in connection with the accompanying drawings, which show the preferred embodiment of the invention.

In these drawings, Figure 1 is an elevation, broken away and sectioned in part, of one end of the engine, Fig. 2 is a sectional elevation on an enlarged scale showing the air cylinder and parts associated therewith, Figs. 3 and 4 are horizontal sectional views on lines 3—3 and 4—4 of Fig. 2, Fig. 5 is a sectional elevation of the shiftable casing by which changes are effected in the angular relation of the cam shaft to the engine shaft, Figs. 6 and 7 are horizontal sectional views on lines 6—6 and 7—7 of Fig. 5, and Fig. 8 is an elevation, partially diagrammatic, of a portion of an internal combustion engine constructed in accordance with the invention.

Referring to these drawings, an engine is shown having a plurality of cylinders 9 which are mounted in the usual manner upon a casing 10 inclosing the crank-shaft 11 and the connecting rods which connect the crank-shaft with the pistons in the several cylinders. Any suitable mechanism may be provided for admitting fuel to the cylinders. The invention is of special utility in connection with Diesel engines in which the fuel is admitted to the cylinders in liquid form.

The admission of the fuel to the cylinders and the admission of compressed air to the cylinders when starting the engine is effected by air under the control of a cam shaft 12, which is shown as extending along the upper ends of the cylinders and journaled in bearings formed therein. This cam shaft is driven by the crank-shaft 11 at a speed bearing a definite relation to the speed of the shaft 11. For this purpose the shafts 11 and 12 are provided with gears 13 and 14, respectively, meshing with coacting gears 15

and 16, respectively, on a vertically disposed connecting shaft. This shaft is shown as formed of two parts 17 and 18 mounted for rotation in suitable bearings and in axial alignment. The two parts 17 and 18 of this shaft are connected together in a definite relation for operation of the engine in one direction and when reversal of the engine is to be effected, the two parts 17 and 18 of the connecting shaft are shifted angularly, one relative to the other, so that the angular relation of the cam shaft 12 to the crank-shaft 11 is changed to a predetermined extent. In this way, the cams on the shaft 12 are turned through a definite angle unaccompanied by turning movement of the crank-shaft so as to establish them in the new relation required for operation of the engine in the opposite direction. This angular shifting of the relation of the parts 17 and 18 of the connecting shaft is effected by axial movement of the means employed for connecting the parts 17 and 18, this means having spirally arranged grooves associated therewith so that its axial movement results in turning the part 18 of the connecting shaft and hence the cam shaft 12 through the desired angle, since the crank-shaft 11 and the part 17 of the connecting shaft 18 are held against turning. Secured on the shaft 17 at the upper end thereof, is a collar 19 (Fig. 5) having a plurality of spirally arranged grooves in the outer surface thereof. These grooves receive shoes 20 which are secured by means of pins 21 upon the interior wall of a casing 22 which incloses the collar 19. This casing 22 is also connected to the lower end of the shaft 18, this connection being a spline as shown at 23, so that, though the casing 22 may move vertically with relation to shaft 18, the casing 22 and shaft 18 always rotate together. The portion of the casing 22 inclosing the lower end of shaft 18 is provided with a circumferential groove adapted to receive a two-part ring 24 pivoted to an operating lever 25 whereby the casing 22 is moved vertically. It will be seen that when the shaft 17 is held against rotation by the crank-shaft and the casing 22 is moved vertically, the shaft 18 and the cam shaft connected thereto will be turned in their bearings an amount depending upon the extent of movement of casing 22 and the pitch of the spirally arranged grooves in the collar 19. The turning movement of the shaft 18 and the cam shaft effected in this way, is such that the cams on the cam-shaft will be shifted the amount necessary to effect reversal of the direction of rotation of the engine.

The operating lever 25 is pivotally mounted intermediate its ends upon the lower end of a link 26, whose upper end is pivoted upon the casing of the engine. The

end of lever 25 opposite to that connected to casing 22 is connected by means of a link 27 to the lower end of the rod 28 of a piston located in an air cylinder. This rod 28 is extended upwardly through the air cylinder 70 and carries the piston of a dash-pot whereby the movements of the casing 22 are controlled and too rapid or irregular movement thereof prevented.

The construction of the air cylinder just referred to and the parts associated therewith, is shown in detail in Figs. 2, 3, and 4. The air cylinder is shown at 29. At its ends it is provided with stuffing-boxes through which the rod 28 extends. The dash-pot is 80 shown at 30 having stuffing-boxes at its ends through which rod 28 extends and having a piston 31 secured on rod 28 and reciprocating within the cylinder of the dash-pot. The cylinder 29 is provided with a piston 32 85 secured on the rod 28.

The lever 25 is extended a short distance beyond the point of connection to the link 27 and its extreme end is connected by a link 33 (Fig. 1) to a slide 34, shown in Figs. 1 90 to 4. This slide is received in a vertically disposed guide-way provided for its reception in the casting of the cylinder 29 and it is held in position in the guide-way by a cover-plate 35 which is secured to the casting 29. The slide 34 is engaged by one or the other of two locking pins 36 and 37, the latter of which is shown in detail in Fig. 3. Each of these locking pins has a piston 38 secured thereon or formed integral therewith 100 and adapted to reciprocate horizontally in a small cylinder formed in the casting for the air cylinder 29. Also, each of these small cylinders is closed at one end by a threaded plug 39 shaped to receive a spring 105 40 by which the piston 38 and the locking pin secured thereto are pressed in a direction to carry the end of the locking pin into a coacting opening in the slide 34. A port 41 leads into the cylinder for the piston 110 which carries the locking pin 37 at the end of that cylinder adjacent to the slide 34; a similar port leads to the corresponding end of the upper cylinder for the piston which carries the locking pin 36. From each of these cylinders, a port 42 leads to the cylinder in which the piston 32 reciprocates, this port 42 entering the cylinder for the piston 32 at the adjacent end of the cylinder, as shown in Fig. 2. It will be seen that when air under pressure is admitted through port 41, it acts upon the piston 38 so as to move it against the tension of spring 40 until the corresponding locking pin is withdrawn from the opening in slide 34 and after the 115 locking pin has been so withdrawn from its locking relation to slide 34, the piston 38 opens the port 42 so that the air admitted to the port 41 may pass through the port 42 and into the cylinder 29 to act on the piston 120 32. The piston 38 is held in the cylinder 125 29 by the tension of spring 40 until the locking pin 37 is again withdrawn from its locking relation to slide 34, the piston 38 then closing the port 42 so that the air admitted to the port 41 may not pass through the port 42 and into the cylinder 29 to act on the piston 130 32.

32 therein and reciprocate the latter. The reciprocation of piston 32 effects rocking movement of the lever 25 and shifts the casing 22 and this rocking movement of lever 25 causes the slide 34 to move vertically. After the vertical movement of the slide 34 has begun, the locking pin which was withdrawn cannot again come into its locking position with respect to the slide, for even if 10 the spring 40 be permitted to move the piston 38 and the locking pin, the latter will engage the side of the slide 34 and be arrested thereby. When the movement of the piston 32 and slide 34 have been completed, 15 the other locking pin will be moved by its spring 40 to project its end into the corresponding opening in the slide 34 so as to hold the slide against movement until air is admitted to the cylinder of that locking 20 pin to withdraw it as above described.

In the wall of the cylinder 29 are two ports 43 and 44 which are controlled by the piston 32. These ports are so located that they are closed until the piston nears the end 25 of its movement in one direction or the other. Just as the piston approaches the limit of its movement in one direction, it opens one of the two ports so that air may pass through the cylinder and out through 30 that port.

Fig. 8 shows the air connections diagrammatically. A conduit leading from a source of supply of compressed air is shown at 45 and this conduit is connected to a valve 46 from which pipes 47 and 48 lead to the ports 41 of the upper and lower locking pins 36 and 37, respectively. The valve 46 is provided with an exhaust port 49 and is so constructed that either of the two pipes 47 and 48 may be connected to the supply pipe 45 and the other to the atmosphere at 49. The ports 43 and 44 leading from the air cylinder are connected together and to the devices for admitting starting air to the cylinders 9 of the engine by means of conduits 50. The valves by which the starting air is admitted to the cylinders 9 may be arranged to be actuated mechanically by cams on the cam shaft 12, or if desired these valves 50 may be pneumatically actuated. In the construction illustrated in the drawings, the air-inlet valves 51 on the several cylinders 9 are shown as adapted to be actuated mechanically by cams on the cam shaft and 55 the conduit 50 is therefore shown as extending from the cylinder 29 to all of the air-inlet valves 51. If desired, the several air-inlet valves 51 may be pneumatically actuated and in that case the air flowing from 60 the cylinder 29 to the valves 51 would be merely the actuating air, the air admitted to the cylinders 9 being led to the valves 51 by another conduit. In this latter case, a suitable distributor driven by the engine 65 shaft would be provided for controlling the

supply of the actuating air from the cylinder 29 to the several pneumatically actuated valves 51 successively in the desired order and at the proper time intervals.

The operation of the mechanism constructed as above set forth will now be described. Figs. 2, 3 and 4 show the parts in the positions which they occupy when the engine is set for running in a given direction. The lower locking pin 37 has been moved by its 70 spring 40 to the operative position in which the end of the pin lies in an opening in the slide 34 so that the slide, the piston 32, the lever 25 and the casing 22, are all positively locked against unintended movement thereof. 75 The upper locking pin 36 is in a slightly retracted position with its end in contact with the side of the slide 34, the hole in the slide for the reception of the end of pin 36 being below the pin. If the engine were at rest, 80 the handle of the valve 46 would be in a neutral position. To start the engine in the direction for which the parts thereof had already been set, the handle of the valve 46 would be turned to the position for admitting 85 air from the conduit 45 to the pipe 47 and to the port 41 of the upper locking pin 36. From that port the air would flow to the port 42, moving the piston 38 back a short distance if necessary, and this air passing 90 through port 42 would flow through the cylinder 29, port 43 and conduit 50 into that one of the several cylinders whose piston was in the appropriate position. The air flowing to the cylinders thus would be admitted to 95 the cylinders in the proper sequence by means of the cams controlling the several air-inlet valves and the starting of the operation of the engine would thus be effected. 100 When the engine began to operate under its own power, the handle of the valve 46 would be turned to the neutral position. 105

If it were desired to operate in the opposite direction, the engine would be brought to rest and the handle of valve 46 would be moved to the position for admitting air from the conduit 45 to the pipe 48. From this pipe the air would flow through the port 41 of the lower locking pin 37 and would act 110 on the piston 38 of that pin so as to retract the pin from its opening in the slide 34. Having done this, the air would be permitted to flow through the port 42 leading to the lower end of the cylinder 29 and would act 115 upon the piston 32 so as to force the latter upwardly in the cylinder 29. This upward movement of the piston 32 would take place immediately after the slide 34 had been unlocked by the retraction of pin 37 and would result in rocking the lever 25 so as to shift 120 the casing 22. This movement of the casing 22 would turn the shaft 18 as above described so as to effect the requisite turning movement of the cam shaft 12. At the completion of 125 the upward movement of the piston 32 that 130

is, after the cam shaft 12 had been turned as required, the piston 32 would open the port 44 so that air would flow from the cylinder 29 into the conduit 50 leading to the air-inlet valves 51. This air would be admitted to the cylinders successively in the manner above described so as to start the engine in the reverse direction and continue it in operation until it began to operate under its own power. Also, the upward movement of the piston 32 within the cylinder 29 would be accompanied by upward movement of the slide 34 and when these parts reached the end of their upward movement, the upper locking pin 36 would be moved outwardly by its spring 40 to carry the end of the pin into its opening in the slide 34 so that the slide and the other parts of the reversing gearing would be again locked so that they could not be moved until air was admitted to the cylinder of the upper locking pin to effect the withdrawal of that pin. It will thus be seen that the parts employed in reversing the direction of operation of the engine are positively locked against movement at all times except when they are intentionally unlocked for the purpose of effecting the reversal. Furthermore, this locking mechanism, the mechanism for reversing the engine and the mechanism for starting the engine are all controlled from a single point and preferably by means of a single valve. The opening of this valve first effects the withdrawal of the pin 36 or 37 which at that time is serving to lock the mechanism, then moves the parts of the reversing mechanism to the reverse position and then, without further manipulation, admits air to the cylinders of the engine so as to start the engine in operation. The air cannot enter the cylinder 29 to move the piston 32 and shift the casing 22 until after the locking pin has been withdrawn from its locking position; also, the air admitted to cylinder 29 cannot flow from that cylinder to the inlet valves of the engine until after the piston 32 and the casing 22 have completed their movement. This latter insures that the parts of the reversing mechanism will have completed their movement of reversal before the operation of the engine has begun by the air employed in starting. In this way certain defects of operation are avoided which result from starting the engine in operation slightly in advance of completing the movement of the parts employed for reversing the direction of the operation of the engine. Furthermore, when the movement of the parts employed in reversing the direction of operation of the engine has been completed, those parts are automatically and positively locked and thereafter are held against unintended movement.

66. An important feature of the construction

herein shown and described is that a definite sequence of operations is established and one operation must be completed before another is begun so that there is little or no danger of injury to the mechanism due to carelessness or inattention on the part of the operator.

While we have illustrated and described herein the construction which we prefer to employ, it is to be understood that the invention is not limited to this particular construction but that the same may be varied in numerous respects without departing from the invention. The casing 22 and the spiral grooves with which it coacts are shown as located at the point where the shaft connecting the engine shaft and cam shaft is divided. If desired, however, these parts may be located at a different point in the connection from the engine shaft to the cam shaft, as for instance, at the connector of one of the gears employed to its shaft. Also, any desired form of connection of the air cylinder to the casing 22 may be employed other than the simple form of pivoted lever 25 herein shown. In some types of engines a plurality of cam shafts are employed instead of one as in the engine illustrated, and in such case the air cylinder may be arranged to shift all of the cam shafts by means of suitable gearing, the several cam shafts being shifted through the same or different angles as may be required by the functions which they are to serve.

What we claim is:

1. The combination of an internal combustion engine including air-starting means therefor, a reversing control for the engine, and an air-supply line for supplying compressed air to operate both the reversing control and the air-starting means, said reversing control and said air-starting means being connected in the air-supply line in series; substantially as described.

2. The combination of an internal combustion engine including an air starting means therefor, a reversing control for the engine, and a single means for operating the reversing control and for operating the air starting means after the reversing control has completed its movement of reversal, said single means including an air-line within which are interposed in series said reversing control and said air-starting means; substantially as described.

3. The combination of an internal combustion engine including an air-starting valve, a normally closed air-line for said valve, a reversing control for the engine, and a single pneumatically operated piston moving when actuated to operate the reversing control and to open said line; substantially as described.

4. The combination of an internal combustion engine including an air-starting

100

105

110

115

120

125

130

valve, a normally closed air-line for said valve, a reversing control for the engine, and a single pneumatically operated piston interposed in said line and moving when actuated first to operate the reversing control and after said reversing control has completed its movement of reversal to open said line; substantially as described.

5. The combination of an internal combustion engine, air-starting means therefor, a reversing control for the engine, means for actuating the reversing control, and a normally closed air-line opened directly by the actuation of the said means to feed actuating air to the air-starting means; substantially as described.

6. The combination of an internal combustion engine including air-starting means therefor having valves and valve-controllers, a reversing means for the engine, a pneumatically actuated control for operating the reversing means, an air-line normally out of communication with the air-starting means, and a normally inoperative means which is rendered operative by the movement of said pneumatically actuated control to place said air-line in communication with the air-starting means and make the latter operative in response to the operation of the valve-controllers after the reversing means has been actuated; substantially as described.

7. The combination of an internal combustion engine, a reversing control therefor, a plurality of separate locking devices one of which engages with the reversing control in each of two positions of the latter, and means for pneumatically operating the engaging locking device to release the reversing control and for then pneumatically operating the reversing control; substantially as described.

8. The combination of an internal combustion engine, a reversing means therefor including a pneumatically operated control, a bolt for locking the control, a pneumatically operated device for displacing the bolt to release the control, and a normally ineffective air-line for operating the control which air-line is rendered effective by the movement of said device; substantially as described.

9. The combination of an internal combustion engine, a reversing control therefor, a plurality of separate locking devices for the reversing control one of which engages with the reversing control in each of two positions of the latter, and a single means for operating the engaging locking device to release the reversing control and then to operate the reversing control, the other locking device being actuated automatically to engage the reversing control after the latter has been operated; substantially as described.

65 10. The combination of an internal com-

bustion engine including air-starting means therefor, a reversing control therefor, an air-line normally out of communication with the air-starting means, a plurality of separate locking devices for the reversing control one of which engages with the reversing control in each of two positions of the latter, a single means for operating the engaging locking device to release the reversing control, the other locking device being actuated automatically to engage the reversing control after the latter has been operated, and means for opening said air-line to operate said air-starting means controlled by the movement of the reversing control; substantially as described.

70 11. The combination of an internal combustion engine, an air-starting means therefor, a reversing means therefor including a pneumatically operated control, a lock for the control, a pneumatically operated device for actuating the lock to release the control, and an air-line normally ineffective to operate either the control or the air-starting means, said air-line being by the operation of said device rendered effective to operate said control and said air-line being by the operation of said control rendered effective to supply air to said air-starting means; substantially as described.

75 12. The combination of an internal combustion engine, an air-starting means therefor, a reversing control for the engine, a plurality of locking devices for the reversing control, an air supply line having interposed therein in series one of said locking devices, said reversing control and the valves of said air-starting means, and a single means for operating the locking device last mentioned to release the reversing control and render said line effective to operate the reversing control, for then operating the reversing control and rendering said line effective to feed air to the air-starting means, and for then feeding air through said line to said air-starting means; substantially as described.

80 13. The combination of an internal combustion engine, an air-starting means therefor, a reversing control for the engine including a pneumatically operated piston, locking means for the reversing control including a pneumatically operated piston, and an air-supply line having interposed therein in series the first mentioned piston, the second mentioned piston and said air-starting means; substantially as described.

85 14. The combination of an internal combustion engine, reversing means therefor including a piston, a cylinder within which said piston is located, means for admitting air to the cylinder to move the piston and thereby to cause a reversal of the engine, and a connection from said cylinder to the cylinders of the engine for conveying air to

the cylinders of the engine to start the engine when thus reversed; substantially as described.

15. An internal combustion engine having the combination of a crank shaft, a cam shaft, a divided connecting shaft geared to said shafts, a member connecting the two parts of said divided shaft to cause simultaneous rotation thereof, said member being movable in the direction of the length of the divided shaft and connected to one of the parts thereof by spiral threads, and pneumatically actuated devices for reciprocating said member; substantially as described.

15. 16. The combination of an internal combustion engine, a reversing means therefor including a piston movable to reverse the engine, a cylinder within which said piston is located, a locking bolt, a second piston controlling the position of the locking bolt, a cylinder within which the second piston is located, a member movable with the reversing means and engaged by said bolt when the reversing means is in one of the running positions, an air-line leading from a source of supply to the second piston's cylinder to supply air thereto for displacing the second piston to disengage the bolt from said member, and an air-passage leading from the second piston's cylinder to the first piston's cylinder which air-passage is opened by the movement of the piston in the second cylinder to actuate said locking bolt; substantially as described.

35. 17. The combination of an internal combustion engine, a reversing means therefor including a piston movable to reverse the engine, a cylinder within which said piston is located, a locking bolt, a second piston controlling the position of the locking bolt, a cylinder within which the second piston is located, a member movable with the reversing means and engaged by said bolt when the reversing means is in one of the running positions, an air-line leading from a source of supply to the second piston's cylinder to supply air thereto for displacing the second piston to disengage the bolt from said member, an air-passage leading from the second piston's cylinder to the first piston's cylinder, which air-passage is opened by the movement of the piston in the second cylinder to actuate said locking bolt, and an air connection from the first cylinder to the air-starting valves of the engine; substantially as described.

18. The combination of an internal combustion engine, a reversing means therefor including a piston movable to reverse the engine, a cylinder within which said piston is located, a locking bolt, a second piston controlling the position of the locking bolt, a cylinder within which the second piston is located, a member movable with the reversing means and engaged by said bolt when

the reversing means is in one of its running positions, an air-line leading from a source of supply to the second piston's cylinder to supply air thereto for displacing the second piston to disengage the bolt from said member, an air-passage leading from the second piston's cylinder to the first piston's cylinder which air-passage is opened by the movement of the piston in the second cylinder to actuate said locking bolt, and a connection leading to the air-starting valves of the engine having its communication with said air-line controlled by the movement of the piston in the first cylinder; substantially as described.

19. The combination of an internal combustion engine, a cylinder, a piston reciprocating therein, a reversing means operated by the piston to set the valve-controllers of the engine for running in one direction when the piston is at one end of said cylinder and to set said valve-controllers for running in the reverse direction when the piston is at the other end of said cylinder, a connection leading from a source of air supply into the upper part of the cylinder, a connection leading from said source into the lower part of the cylinder, a connection leading from the upper part of the cylinder to the air-starting means of the engine, and a connection leading from the lower part of the cylinder to said air-starting means, one of the two last mentioned connections being closed and the other opened by the piston when the latter is at either end of its range of movement within the cylinder; substantially as described.

20. The combination of an internal combustion engine, a cylinder, a piston reciprocating therein, a reversing means operated by the piston to set the valve controllers of the engine for running in one direction when the piston is at one end of said cylinder and to set said valve controllers for running in the reverse direction when the piston is at the other end of said cylinder, a connection leading from a source of air supply into the upper part of the cylinder, a connection leading from said source into the lower part of the cylinder, a connection leading from the upper part of the cylinder to the air-starting means of the engine, and a connection leading from the lower part of the cylinder to said air-starting means, the third mentioned connection being in communication with the first mentioned connection and the fourth mentioned connection being closed by said piston when the latter is in the lower end of said cylinder, the fourth mentioned connection being in communication with the second mentioned connection and the third mentioned connection being closed by said piston when the latter is in the upper end of said cylinder, and both the third and fourth mentioned connections being closed by said

- piston during the major part of the latter's travel from one end of the cylinder to the other; substantially as described.
21. In an internal combustion engine, the combination of the cylinders, air valves thereon for starting, a cam shaft having cams thereon for actuating certain of the valves of the engine, means for shifting said cams to adapt the engine for operation in one direction or the other, a cylinder and a piston therein for actuating said means, and an air-supply conduit for supplying compressed air to the air valves, which conduit is controlled by the position of the piston in said cylinder; substantially as described.
22. In an internal combustion engine, the combination of the cylinders, a cam shaft having cams thereon for actuating certain of the valves of the engine, means for shifting said cams to adapt the engine for operation in one direction or the other, which means is movable to one or the other of two operative positions, air-starting valves on the cylinders, and means for supplying compressed air to said valves which means is effective when said shifting means is in one or the other of its operative positions but not when it is in an intermediate position; substantially as described.
23. In an internal combustion engine, the combination of the cylinders, a cam shaft having cams thereon for actuating certain of the valves of the engine, means for shifting said cams to adapt the engine for operation in one direction or the other, a lock for said shifting means, air-starting valves on the cylinders, a source of supply of compressed air for said valves, and a single means for first operating said lock, then operating said shifting means and then connecting the source of supply of compressed air to the air-starting valves; substantially as described.
24. In an internal combustion engine, the combination of the cylinders, a cam shaft having cams thereon for actuating certain of the valves of the engine, means for shifting said cams to adapt the engine for operation in one direction or the other, a lock for said shifting means, and a single means for first operating said lock to release said shifting means and then operating the shifting means to adapt the engine for operation in the opposite direction; substantially as described.
25. In an internal combustion engine, the combination of the cylinders, a cam shaft having cams thereon for actuating certain of the valves of the engine, means for shifting said cams to adapt the engine for operation in one direction or the other, locking mechanism for said shifting means, and a single means for operating the locking mechanism to release the shifting means and then operating the shifting means to effect reversal of the engine, said locking mechanism being operated automatically after the shifting means has been actuated to again lock the shifting means; substantially as described.

In testimony whereof we affix our signatures, in presence of two witnesses.

GREGORY C. DAVISON.

JOHN W. ANDERSON.

Witnesses:

F. W. BLAKE,
E. C. HUNGERFORD.
